UNITED STATES PATENT OFFICE.

BERNARD J. HAUSFELD AND EDMUND H. LUNKEN, OF CINCINNATI, OHIO;
SAID HAUSFELD ASSIGNOR TO SAID LUNKEN.

WINDOW.

SPECIFICATION forming part of Letters Patent No. 760,625, dated May 24, 1904.

Application filed November 27, 1903. Serial No. 182,860. (No model.)

To all whom it may concern:

Be it known that we, BERNARD J. HAUSFELD and EDMUND H. LUNKEN, citizens of the United States, residing at Cincinnati, in the county of Hamilton and State of Ohio, have invented certain new and useful Improvements in Windows, of which the following is a description, reference being had to the accompanying drawings, forming part of this specification.

10 Our present invention relates to improvements upon and modifications of the window construction illustrated and described in our pending application, Serial No. 173,118, filed September 14, 1903, and its novelty will be 15 hereinafter more fully set forth, and particularly pointed out in our claims.

In the accompanying drawings, Figure 1 is a middle vertical section of a window embodying our invention; Fig. 2, a horizontal cross-section of the same on a larger scale; Fig. 3, a detail section of a portion of the main frame and swinging frame on the dotted line 3 3 of Fig. 2; Fig. 3^a, a corresponding view on the dotted line 3^a 3^a of Fig. 2; Fig. 3^b, a detail sectional plan view on the dotted line 3^b 3^b of Fig. 1. Fig. 3^c is an enlarged sectional plan view on the dotted line 3^c 3^c of Fig. 1; Fig. 3^d, a detail sectional elevation on dotted line 3^d 3^d of Fig. 3^c; Fig. 4, a horizontal sectional 20 view corresponding to Fig. 2, but with the window swung to partially-open position; Fig. 5, a horizontal section on line 5 5 of Fig. 1 immediately beneath the swinging frame of Fig. 4; Fig. 6, an elevation of a modified form 25 of main frame with the swinging frame removed from it; Fig. 7, a horizontal cross-section of the main frame of Fig. 6; Fig. 8, a horizontal sectional detail showing a modification of the main-frame construction; Fig. 30 9, a similar view showing another modification; Figs. 10 and 11, perspective views of the two parts of the hinge employed in Figs. 1 to 5; Fig. 12, a vertical section of the hinge at the bottom of the swinging frame, showing 35 the two parts of Figs. 10 and 11 assembled together; Fig. 13, a detail view showing a modification of the hinge construction, and Figs. 14 and 15 detail views illustrating further modifications.

The same numerals of reference are employed to indicate corresponding parts in the several views.

Our present invention, like our former one, relates to windows in which the sliding glass-carrying frames are mounted in a pivoted or swinging frame, which is in turn mounted in the fixed main frame of the window, the glass-carrying frames being free to slide up and down in the swinging frame, as in ordinary window constructions, while the swinging frame may be swung in the main frame to open the window, both for the purpose of ventilation and for the purpose of bringing the opposite sides of the glass within convenient reach when it is desired to clean the same. In our former application the swinging frame was pivoted midway of its vertical length in the opposite sides of the main frame and swung upon a horizontal axis or pivot, while in our present construction the swinging frame is pivoted at the middle of its top and bottom, and therefore swings upon a vertical axis or pivot.

Certain features of our invention relate to provision for this change in the pivotal arrangement of the swinging frame, while others relate to improvements in the construction of the window, which are applicable to either arrangement of the swinging frame.

Referring now to the construction and arrangement of the parts shown in Figs. 1 to 5 of the accompanying drawings, 1 represents the wall of a building in which is formed a window-opening, of which 2 represents one of its side walls, 3 its top piece or lintel, and 4 its bottom piece or sill, these parts in the present instance being assumed to be of stone, while the side walls 2 of the window-opening are of brick.

The rectangular metal main frame 5 of the window, preferably made up of four separate pieces suitably secured together at the corners of the frame, is of channel or U shape in cross-section and is secured in the window-opening behind the lintel 3 and sill 4 and side walls 2 of the window-opening, with its open or channel side facing outward, as shown. Secured within the window-opening outside of this

metal frame is a wooden frame or casing composed of top and bottom strips 6, 7, Fig. 1; side strips 8, Fig. 2, and front or outer strips 9, Figs. 1 and 2, the strips 9 being (with the exception of the bottom one) nailed to the strips 6, 7, and 8 before the wooden frame composed of them is inserted in position in the window-opening. The front or outer face of the main frame 5 fits against the strips 9 at 10 the top and sides of the window-opening, as shown in Figs. 1 and 2, while at its bottom the frame 5 has its outer or forward side bent outwardly to form a supporting foot or bracket 10, which rests upon the upper edge of the bottom strip 9 of the wooden casing, as shown in Fig. 1, said foot or bracket extending the full width of the main frame and serving to support the latter in position in the window-opening upon the strip 9. This strip 9 may 15 be nailed to the bottom and side pieces 7, 8 of the wooden frame, as are the other strips 9; but we prefer to insert it loosely in place and rest the metal main frame upon it for a purpose hereinafter described.

20 The foot or bracket 10 of the main frame 5 also serves to prevent water at the bottom of the window-opening from passing inward through the joint between the main frame 5 and the wooden strips 9. The joint between 25 the outer face of the main frame 5 and the strips 9 entirely around the window-opening, as well as between the strips 9 and the lintel 3 and sill 4 and side walls 2 of the window-opening, are covered by a finishing-strip 11, extending entirely around the window-opening.

30 Fitting against the inner or rear side of the main frame within the inclosing wooden frame is a rectangular retaining-frame 12, nailed or otherwise secured to the top and bottom and side strips 6, 7, and 8 of the wooden frame heretofore described. The under surface of the top piece of the retaining-frame 12 and the inner faces of the side pieces of said frame are covered by a thin strip of sheet metal 13 35 to hide and protect the wooden frame. This sheet-metal cover may be continued over the bottom of the frame 12; but we preferably cover the upper surface of the bottom piece of the frame with either a thicker strip of metal 40 or a marble slab or other finishing-piece 14. The rear face of the retaining-frame 12 is covered by a metal finishing-strip 15 at the top and sides of the window and at the bottom by a similar strip or a metallic molding 16, Fig. 4. 45 The joint between the inner or rear face of the main frame 5 and the retaining-frame 12 or its sheet-metal covering is covered by a finishing-strip 17, similar to the outer finishing-strips 11, heretofore referred to.

50 The purpose of leaving the bottom strip 9 of the wooden casing detached from the bottom and side pieces 7 and 8 thereof may now be explained, such purpose being to permit said bottom strip to be removed and trued up 55 to compensate for any irregularities produced

by settling of the building or otherwise without the necessity of removing the entire wooden casing even were the latter possible. To obtain access to the strip 9 for this purpose, it is only necessary to remove the wooden 70 retaining-frame 12 and the main frame 5 and bottom finishing-strip 11, whereupon the strip 9 may be lifted out of its position between the bottom piece 7 of the wooden casing and the rear facing of the sill 4 and removed for the 75 purpose of planing off or adding to its upper or lower edges as occasion may require.

Having now described the general window construction, it will next be in order to describe the mounting of the swinging frame in 80 the main frame and its coöperation therewith. As shown most clearly in Fig. 5, this swinging frame 18 is pivoted at top and bottom, midway of its width, on trunnions or pivots 34, hereinafter more particularly described, so 85 that the window is free to swing through approximately a half-revolution either for purposes of ventilation or for the purpose of reversing its position and bringing the outer sides of the glass windows carried by it to the 90 inner side of the window-opening for the purpose of enabling them to be easily reached and cleaned. It is desirable that this swinging frame shall form a tight joint with the main frame 5 entirely around the window 95 when the swinging frame is closed. This is accomplished, as to the sides of the window-opening, by the coöperating angle or L-shaped stop-strips 20 and 21, secured, respectively, to the swinging frame and the main frame 5, as 100 clearly shown in Fig. 4. A packing-strip 22 is interposed between the coöperating strips 20 and 21 to effect a more nearly air and water tight joint between them, which packing-strip may be secured either in the stop-strips 105 20, carried by the swinging frame, or in the fixed stop-strips 21 on the main frame 5; but to protect such packing-strips as much as possible from the weather we secure the left-hand one in Fig. 4 to the fixed stop-strip 21 110 on the main frame and the right-hand one to the stop-strip 20, carried by the swinging frame, so that both will be protected from water and dust and dirt driven toward the window from the exterior when the swinging 115 frame is partially open. The stop-strips 20 and 21 are formed of metal, and while preferably secured to the sides of the metal swinging frame 18 and to the inner faces of the metal main frame 5, respectively, they may 120 be formed integral with those frames.

Secured to the left side of the swinging frame in rear of the stop-strip 20 is a closing-strip 23, while at the opposite side of the window a similar closing-strip 23 is secured to the main frame 5 behind the stop-strip 21, so as to close the space between the swinging frame and the main frame 5 when the window is closed, as shown in Fig. 2. The strips 20 and 23 may of course be merged into one and like- 125 130

wise the strips 21 and 23, the only purpose of providing the two separate strips at each side being to lighten the construction.

At the top and bottom of the window tight joints between the swinging frame and main frame are provided for by stop-strips 24 25, secured in the top and bottom of the main frame 5, and coöperating stop-strips upon the swinging frame 18. The two stop-strips 24 and 25 are clearly shown in elevation at the top and bottom of the window in Fig. 6, where it will be seen that at both the top and bottom of the window the strips 24 and 25 extend in opposite directions from the socket 27, which receives the pivot or trunnion of the swinging frame, said sockets being located midway of the width of the window-frame at its top and bottom. It will also be noticed that the strips 24 are about one-half the width of the strips 25, and therefore project into the window-opening about one-half as far as the latter strips, this unequal projection of the stop-strips 24 and 25 into the window-opening corresponding to the like unequal projection of the coöperating stop-strips from the top and bottom of the swinging frame, as hereinafter described, whereby the narrow stop-strips on the swinging frame, which coöperate with the wide stop-strips 25 upon the fixed frame, are permitted to swing past and clear the narrow strips 24 upon the fixed frame, while yet coöperating with the wide stop-strips 25 to effect a tight joint when the swinging frame is closed, as in the case of the similar stop-strips 35 in our former application heretofore referred to. Both sets of strips are L-shaped in cross-section, as most clearly shown in Figs. 1, 3, and 3^a. In Fig. 6 the channels or grooves in the strip 24 are exposed to view, while those in the strips 25 are upon the farther side of said strips and hidden from view.

The coöperating stop-strips 28 and 29 on the swinging frame are shown in Figs. 3 and 3^a and also in Fig. 5, in which latter the packing 30, secured in the channel of the strip 29, is exposed to view, (Fig. 5 being a horizontal section immediately beneath the body of the swinging frame 18 through the joint between its bottom and the stop-strips 28 and 29, secured thereto,) while the packing 31, secured in the channel of the fixed stop-strip 24, is shown in dotted lines.

As will be understood from the foregoing, when the frame 18 is swung from its position shown in Fig. 4 to closed position, as in the other views referred to, the lower edge of its L-shaped stop-strip 29 (carrying the packing 30) will enter the channel or groove of the reversely-arranged fixed stop-strip 25, as shown in Fig. 5, the upper and outwardly-projecting edge of the latter strip entering the channel or groove of the strip 29 and abutting tightly against the packing-strip 30, as shown. The same will be true in respect to the coöperation of the stop-strips 24 and 28

and interposed packing-strip 31 at the opposite side of the pivot of the swinging frame, while the lower edge of the L-shaped stop-strip 28, carried by the swinging frame, will pass beneath the upper and oppositely-projecting edge of the fixed L-shaped stop-strip 24 and abut tightly against the interposed packing-strip 31. The left-hand end of the packing-strip 30 is curved around the hub of the socket 27, which receives the pivot or trunnion of the swinging frame and is confined between the outer curved surface of said hub and the curved connecting-piece 33; which unites the stop-strips 28 and 29 on the under side of the swinging frame, so that a tight joint is maintained entirely across the window when the swinging frame is closed.

The arrangement and coöperation of the stop-strips at the top of the window are the same as those just described at the bottom of the window.

The pivot or trunnion at the bottom of the swinging frame, which has its bearing in the socket 27 on the bottom of the main frame, Figs. 5 and 6, comprises a tubular bearing 34, 90 having a reduced and exteriorly-threaded upper end, which is screwed into the bottom plate of the swinging frame 18, as best shown in Figs. 11 and 12. Passing through the central bore of this tubular bearing is a screw 19, 95 which has threaded engagement with said bore, but whose lower end, projecting below the tubular bearing, has a plain surface and fits in a circular opening formed to receive it in the main frame 5. In first placing the swinging frame in position in the window-opening this screw 29 is partially unscrewed or retracted, so that its lower end may pass over the surface of the frame 5 as the tubular bearing 34 is engaged with the socket 27. 100 After the parts have been adjusted to proper position, with the screw 19 immediately over the hole for it in the plate 5, the screw is tightened up and its lower end projected into said hole in the plate 5 and the swinging frame 110 thereby positively secured in position in the main frame.

The same construction and arrangement of the socket 27, tubular bearing 34, screw 19, and frame 5 is employed at the top of the window, the two hinges or pivots of the swinging frame being the same. If it be desired at any time to entirely remove the swinging frame from the window-opening, it is simply necessary to partially withdraw the screws 19 at 115 the top and bottom of the frame, which may be readily done with a screw-driver, as their heads are exposed as in Fig. 4, and then swing the frame to partially open position and withdraw it from the window.

The particular construction of the pivot or hinge above described, employing the screws 19, provides a means for positively locking or holding the swinging frame in place and prevents any accidental displacement of it which 120

might be possible in the absence of the screws 19, owing to the open sockets 27, in which the tubular bearing 34 of the swinging frame rests.

- 5 The swinging frame 18 carries the vertically-sliding glass-carrying frames, which are mounted in suitable guideways upon the opposite sides of the frame and separated by the usual parting-strips. The construction of the 10 swinging frame may in these respects be the same as in our previous application; but in the present instance we have illustrated an improved construction in which the vertical sides and top of the frame are rolled from 15 sheet metal of such shape that the frame itself, without any attached guides and parting-strips, will furnish the guideways for the sliding frames and the parting-strips between them. This construction is indicated in Figs. 20 1, 2, 3^b, 3^c, and 3^d, in the latter two figures of which is shown that the frame 18 is so shaped in cross-section as to provide guideways 18^a for the sliding frames and an intermediate parting-strip 18^b to separate them. This parting-strip 18^b projects farther inward for the 25 purpose of stiffening the frame and affording a larger bearing for the sliding sashes than the outer tongues 18^a, which in connection with the parting-strip 18^b form the guides for 30 the sliding sashes, whose exterior sides entering the guideways are provided with the racks 51, which engage with the pinion 50 on each side of the parting-strip 18^b. The pinion 50 is located on line with the meeting-rails of 35 the two sashes and occupies a cut-out portion in the parting-strip 18^b and is free to turn loosely on a screw-stud 55, as seen in Fig. 3^d, which screw-stud has its head passed through the inner wall of the parting-strip 18^b, where 40 it is countersunk, and has its rear end threaded and retained by a piece forming part of the frame 18, into which it is screwed, or by a filling of fireproof material which fills the entire interior of the parting-strip except at 45 that point where the pinion passes through the walls of the parting-strip to engage the rack. The above-described construction of the parting-strip enables us to make the swinging frame of very light rolled metal in 50 which the parting-strip is integral with the guideways and is hollow, but at the same time can be filled with any suitable light material, preferably of fireproof character, which will stiffen the frame and prevent it being 55 warped or bent out of shape. Again, while we have shown as our preferred form of construction the parting-strip as integral with the rest of the swinging frame it is evident that it might be a separate hollow piece suitably secured to the frame, as by brazing, riveting, or in any other convenient manner. In the present instance, as in our former application, the two glass-carrying frames of 60 the window are geared together by racks and 65 pinions, 50 indicating one of the pinions in

Fig. 3^b and 51 the racks meshing with it. These racks 51 are secured upon or formed integral with the inner faces of the metal strips 52, which extend vertically of the sliding frames at their opposite sides and are secured thereto by screws 53. The outer edges of these strips 52, which carry the racks 51, fit in the guideways 18^a of the frame 18, the opposite or inner faces of the sliding frame fitting against the central portion 18^b of the frame 18. To remove the sliding frames from the swinging frame when occasion requires, the screws 53 are withdrawn and the strips 52 and racks 51 first removed, which serves to free the sliding frame from the guideways 80 of the swinging frame and permits their removal. Likewise in assembling the parts the sliding frames are first placed in position in the frame 18 without the strips 52 and the latter afterward applied and secured to the 85 frame by the screws 53.

In Figs. 6 and 7 a modified construction of the main frame of the window is illustrated, in which the rectangular main frame 35 is formed of wooden timbers whose outer corners are covered by angle-irons 36 to prevent 90 warping of the frame.

In Fig. 8 a wooden main frame is also shown in which the timbers composing it are entirely surrounded, excepting upon their sides 95 facing the window-opening, by a sheet-metal covering 37 to protect the timber from the dampness of the wall and prevent rotting.

In Fig. 9 the wooden main frame is shown composed of three timbers 38, 39, and 40, 100 each tapering in cross-section, and the wall of the building is provided with a dovetailed recess to receive them. The outer timbers 38 and 40 are first placed in position and then locked therein by the middle timber 39, the 105 latter being retained in place by metal plates 41, extending across the joints between it and the outer timbers and secured to them by screws. This construction permits the removal of the main frame from the wall of 110 the building by withdrawal of the middle locking-timber 39, if occasion requires.

In both Figs. 8 and 9 the stop-strips 21 are let into recesses in the timbers of the main frame and secured by screws 42. 115

Figs. 10, 11, and 12 illustrate our preferred construction and arrangement of the parts of the hinge or pivot of the swinging frame, as heretofore described, while Figs. 13, 14, and 15 illustrate modifications which may be employed, if desired. In Fig. 13 the socket 27, which is open in Fig. 10, is provided with a closing-piece 27^a, adapted to be secured to the body of the socket by screws 27^b. When this closed form of socket is employed, the screw 125 19 of Figs. 11 and 12 may be omitted and the tubular bearing 34 alone employed, or such bearing be made solid instead of tubular.

In Figs. 14 and 15 the socket 27 is shown of circular and permanently-closed form, in 130

employing which the tubular bearing-piece 34 will be inserted in place in the socket before the swinging frame is placed in position and the screw 19 be then passed downward through the bottom of the swinging frame into the bearing 34, as shown in Fig. 15.

While in all of the constructions of hinge which we have illustrated and described the socket has been shown secured to or forming part of the main frame and the trunnion or pivot secured to the swinging frame, it is evident that the locations of these coöperating parts of the hinge may be reversed and the socket placed upon the swinging frame and the trunnion upon the fixed frame.

While we have shown our main metallic frame 5 as of channel or U form in cross-section, it is evident that it would be no departure from our invention to make said frame of tubular form substantially rectangular in cross-section, and this frame, like the parting-strip above described, might be filled with any light stiffening material, preferably fire-proof, to give rigidity to it and prevent its being warped or bent out of shape.

Having thus fully described our invention, we claim—

1. In window construction for buildings, a main frame removably secured in position in the window-opening, in combination with a swinging frame pivoted at or near its center in said main frame, coöperating stop-strips upon the main and swinging frames for effecting tight joints between them, said stop-strips on either side of the pivots projecting unequal distances into the window-opening and vertically-sliding glass-carrying frames mounted in guideways in the swinging frame, substantially as described.

2. In window construction for buildings, an outer wooden casing or frame secured in position in the window-opening, an independent metallic main frame fitting within said outer wooden frame or casing, and a retaining-frame also secured within said outer casing and serving to hold the metallic frame in place therein; substantially as described.

3. In window construction for buildings, a main frame, a sash carried thereby, a casing fitted to the space between the main frame and the wall of the window-opening and lying along the sides and outer face of the frame and means for holding the main frame within the casing-frame, substantially as described.

4. In window construction for buildings, a main frame, a sash carried thereby, a casing to be placed between the main frame and the wall of the window-opening, a removable retaining-frame for holding the main frame within the casing, said main frame being adjustable in a vertical plane within the said casing, substantially as described.

5. In window construction for buildings, an outer wooden casing or frame of angular or L shape in cross-section, secured in position

in the window-opening, a metallic main frame of channel or U shape in cross-section fitting within said outer wooden frame or casing, and a retaining-frame also secured within said outer casing and serving to hold the metallic frame in place therein; substantially as described.

6. In combination in a window construction, a main frame, a casing, said main frame being arranged adjustably within the casing and means for holding the main frame in place in the casing, substantially as described.

7. In combination in a window construction, a main frame, a sash carried thereby, a casing within which the main frame is adjustably mounted and means for adjustably blocking up the main frame within the casing, substantially as described.

8. In combination in a window construction, a main sash-carrying frame, a casing in which said main frame is movably fitted, said main frame having a projecting foot and a strip or block upon which the said foot rests, substantially as described.

9. In window construction for buildings, an outer casing or frame of angular or L shape in cross-section secured in the window-opening, the vertically-disposed member of the bottom of said frame being made detachable from the remainder of the frame, in combination with a main frame located within said outer frame or casing and resting upon the detachable bottom member thereof, and a retaining-frame for holding the frame in position in the window-opening; substantially as described.

10. In window construction for buildings, an outer wooden casing or frame of angular or L shape in cross-section located in the window-opening, the vertically-disposed member of the bottom of said frame being left detached from the body of the frame, in combination with a metallic main frame of channel or U shape in cross-section fitting within said outer wooden frame and resting upon the detached bottom member thereof, and a retaining-frame secured in the window-opening behind said main frame and serving to hold it in position; substantially as described.

11. In window construction for buildings, an outer wooden casing or frame of angular or L shape in cross-section fitted into the window-opening and having the vertically-disposed member of its bottom left detached from the body of the frame, in combination with a metallic main frame of channel or U shape in cross-section located within said outer frame or casing and having the wall of its bottom member bent outwardly to form a supporting foot or bracket resting upon the detached member of the outer frame, and a retaining-frame fitted into the window-opening behind said metallic frame and serving to secure the latter in position; substantially as described.

12. In window construction for buildings a

- removable supporting piece or timber disposed across the bottom of the window-opening, in combination with a main frame adjustably held within the window-opening and resting upon said supporting piece or timber, and means for securing said main frame in position in the window-opening, substantially as described.
13. In window construction for buildings, a removable wooden supporting piece or timber disposed horizontally across the bottom of the window-opening, in combination with a metallic main frame adjustably held in the window-opening and resting upon said timber, and means for removably securing said main frame in position in the window-opening; substantially as described.
14. In window construction for buildings, the combination of the outer wooden casing or frame comprising the top and bottom pieces 6 and 7, and side pieces 8, and outer strips 9, in combination with the metallic main frame 5 located within said outer frame and resting upon the bottom member 9 thereof, and the retaining-frame 12 for securing the frame 5 in place; substantially as described.
15. In window construction for buildings the outer wooden frame or casing comprising the top and bottom pieces 6 and 7, and side pieces 8 and the front pieces 9, the bottom one of the latter being left detached from the bottom and side pieces 7, 8 of the frame, in combination with the metallic frame 5 having its bottom member bent outward to form the foot 10 resting upon the strip 9, and the retaining-frame 12 for holding the frame 5 in position; substantially as described.
16. In window construction for buildings, the combination of the side walls 2 and top and bottom walls 3, 4, of the window-opening, having the enlarged opening in their rear, the outer wooden frame or casing fitting in the enlarged opening in rear of said side and top and bottom walls and having its front members 9 abutting against the rear faces of said side and top and bottom walls, the metallic frame 5 of channel or U shape in cross-section located within said outer frame or casing and fitting against the rear faces of the top and bottom and side members 9 of said casing and resting upon the bottom member thereof, the retaining-frame 12 secured in the enlarged portion of the window-opening and fitting against the rear side of the metallic frame 5, the finishing-strips 11 and 17 upon opposite sides of the frame 5, and the metal covering-strips 13 and 15 applied to the retaining-frame 12; substantially as described.
17. In window construction, with a window-opening enlarged at the rear, an L-shaped casing fitting in the said enlarged opening and abutting the shoulder formed by the wall about the reduced part of the opening, a main frame fitting in the casing and bearing upon both parts of the L-shaped casing and a retaining-frame fitted against the main frame to hold the same within the casing, substantially as described.
18. In window construction for buildings, the combination of the side walls 2 and top and bottom walls 3, 4 of the window-opening, having the enlarged opening in their rear, the outer wooden frame or casing fitting in the enlarged opening in rear of said side and top and bottom walls and having its front members 9 abutting against the rear faces of said side and top and bottom walls, the metallic frame 5 of channel or U shape in cross-section located within said outer frame or casing and fitting against the rear faces of the top and bottom and side members 9 of said casing and resting upon the bottom member thereof, the frame 12 secured in the enlarged portion of the window-opening and fitting against the rear side of the metallic frame 5, the finishing-strips 11 and 17 upon opposite sides of the frame 5, and the metal covering-strips 13 and 15 applied to the retaining-frame 12; substantially as described.
19. In window construction for buildings, a main frame secured in position in the window-opening, a swinging frame pivoted at top and bottom in said main frame, coöperating tongued and grooved stop-strips upon the two frames for effecting tight joints between them, packing-strips interposed between the coöperating stop-strips, and vertically-sliding glass-carrying frames mounted in guideways in the swinging frame, substantially as described.
20. In combination, a main frame, a swinging frame pivotally mounted therein, a pair of balanced sliding sashes in the swinging frame and a casing fitting between the main frame and the wall of the window-opening, substantially as described.
21. In window construction for buildings, the combination of a metallic frame having guideways therein for a pair of sashes, said guideways being formed by two end guide-strips and a central parting-strip, said end guide-strips and central parting-strip being formed of one piece of metal, and each of said sashes having a strip removably secured to the exposed face thereof and extending into the guideways, to removably hold the sash therein substantially as described.
22. In combination in a window construction, a main frame having guideways, and a sash having a strip removably secured to the exposed face thereof and extending into one of the said guideways, to removably hold the sash therein, substantially as described.
23. In combination in a window construction, a main frame having guideways, a sash having a strip removably secured thereto and extending into the guideway and provided with teeth and a balancing-pinion meshing with said teeth.
24. In window construction for buildings,

the herein-described hinge, comprising the socket 27 secured to or formed upon one member, the tubular bearing 34 fitting within said socket, and the screw 19 carried by the opposite member and screwed into said tubular bearing; substantially as described.

25. In window construction for buildings, the herein-described hinge, comprising the socket 27, secured to or formed upon one member, the tubular bearing 34 projecting from the opposite member and fitting in said socket, and the screw 19 passing through and threaded in said tubular member and having a bearing-surface fitting a bearing formed in the member which carries the socket, substantially as described.

26. In window construction, the combination of a stationary frame in the window-opening, a swinging glass-carrying frame pivoted in said stationary frame, guideways for the glass-carrying-sash frames in said swinging frame, said guideways being partially formed by and separated from each other by central parting-strips, pinions pivotally mounted in cut-out portions of said parting-strips, and racks upon the glass-carrying-sash frames with which said pinions engage.

27. In window construction, the combination of a stationary frame in the window-opening, a swinging glass-carrying frame pivoted in said stationary frame, metallic guideways for the glass-carrying-sash frames in said swinging frame, said guideways being partially formed by and separated from each other by metallic hollow central parting-strips capable of being filled with suitable material, pinions pivotally mounted in cut-out portions of said parting-strips and supported loosely on studs carried entirely by said parting-strips, and racks upon the glass-carrying-sash frames with which said pinions engage.

28. In window construction for buildings, the combination of the fixed main frame 5, the socket-piece 27 thereon, the swinging frame 18, the tubular bearing 34 projecting therefrom and fitting in the socket-piece 27, and the screw 19 passed through and threaded

in the tubular bearing 34 and having its extremity projecting beyond said tubular bearing and shaped to enter and have a bearing in a hole in the frame 5; substantially as described.

29. In window construction for buildings, the herein-described hinge comprising the socket 27 secured to or formed upon one member, and the closing-cap 27^a for said socket, in combination with the bearing 34 projecting from the opposite member and fitting in said socket; substantially as described.

30. In window construction for buildings, the herein-described hinge comprising the socket 27 secured to or formed upon one member, and the closing-cap 27^a therefor, in combination with the tubular bearing 34 projecting from the opposite member, and the screw 19 passing through and threaded in said tubular bearing and having its extremity projecting beyond the same and shaped to enter and have a bearing in a hole in the member carrying the socket 27, substantially as described.

31. In combination, an L-shaped casing, a main frame, a swinging frame carried thereby, said casing being located within the window-opening and means for holding the main frame in place, substantially as described.

32. In window construction; the combination of a frame having a central parting and end guide strips forming guideways for a pair of sashes, said sashes composed of glass-retaining strips on either side of the glass, one of which glass-retaining strips of each sash, has a rack attached thereto, and bears against the end strip and projects farther into the guideway than does the other parts of the sashes, and the pinion connecting the sashes lying partly behind the edge of the least projecting part of the sashes, substantially as described.
